(57) **CLAIM**

The ornamental design for a decorative escutcheon with handle punchout and pressure adhesive backing, as shown and described.

DESCRIPTION

FIG. 1 is a perspective view of a decorative escutcheon with handle punchout and pressure adhesive backing embodying the design of the present invention; the broken lines depict environmental structure and form no part of the claimed design.

FIG. 2 is a front elevational view thereof, the rear elevational view being identical thereto;

FIG. 3 is a left side elevational view thereof, the right side elevational view being identical thereto;

FIG. 4 is a top plan view thereof; and,

FIG. 5 is a bottom plan view thereof.

1 Claim, 2 Drawing Sheets

FIG. 4.

FIG. 5.

FIG. 3.
